US00D942500S

(12) United States Design Patent (10) Patent No.: US D942,500 S
(45) Date of Patent: * Feb. 1, 2022

(54) DISPLAY PANEL WITH GRAPHICAL USER INTERFACE

(71) Applicant: UBII LLC., Boca Raton, FL (US)
(72) Inventors: Rebecca Noble, Boca Raton, FL (US);
Sergio Salani, Boca Raton, FL (US)
(73) Assignee: UBII LLC, Boca Raton, FL (US)
() Term: 15 Years
(21) Appl. No.: 29/674,302
(22) Filed: Dec. 20, 2018
(51) LOC (13) Cl. 14-04
(52) U.S. Cl. D14/489
